A. G. CAMERON

WINDOW FASTENER

Filed Oct. 4, 1926

Patented Dec. 27, 1927.

1,654,361

UNITED STATES PATENT OFFICE

ALEXANDER G. CAMERON, OF WINNIPEG, MANITOBA, CANADA.

WINDOW FASTENER.

Application filed October 4, 1926. Serial No. 139,529.

The invention relates to improvements in window fasteners and an object of the invention is to provide a device which can be readily attached to an existing window and which will permit of the easy adjustment of the sashes in the frame and which will effect the positive fastening of the sashes in their closed positions and which when properly adjusted will hold either of the sashes in selected open positions.

A further object is to construct the device so that the lower sash can be opened a predetermined amount for ventilating purposes and positively fastened in that position against movement in any direction.

A further object of the invention is to provide releasable means for fastening the upper sash closed during the interval that the lower sash is being adjusted.

A further object of the invention is to construct the appliance in a simple, durable and inexpensive manner and such that it can be readily attached to the existing window.

With the above more important objects in view, the invention consists essentially in the arrangement and construction of parts hereinafter more particularly described, reference being had to the accompanying drawing, in which:

Fig. 1 is an interior view of a portion of a window showing my invention applied thereon.

Fig. 2 is an enlarged detailed view of the operating parts associated with the lower end of the rod.

Fig. 3 is an enlarged detailed vertical sectional view at 3—3' Figure 1, the rod being shown in side elevation.

Fig. 4 is an enlarged detailed horizontal sectional view at 4—4' Figure 1.

Fig. 5 is a perspective view of the lower spring casing.

Fig. 6 is a perspective view of the lower spring.

Fig. 7 is an enlarged detailed vertical sectional view at 7—7' Figure 1.

Fig. 8 is a perspective view of the catch associated with the upper sash.

In the drawing like characters of reference indicate corresponding parts in the several figures.

The window frame 1 of customary design is provided with the usual upper sash 2 and lower sash 3 which slide vertically in the customary channels 4 and 5 provided between the usual battens 6 and parting strip 7.

My device is adapted for use on unbalanced sashes and comprises the parts now described. An upper substantially L-shaped bracket 8 is permanently secured such as by screws to the upper end of one of the inner battens and a further bearing bracket 9 is secured to the said batten in a location adjacent the upper end of the lower sash. The brackets are vertically aligned and support rotatably a vertically disposed circular rod 10, the upper end of which is swivelly mounted in the horizontal arm of the upper bracket and the lower end of which is rotatably mounted in the bearing of the bracket 9 and has the extremity thereof turned at right angles to provide a handle 11.

To one of the upper corners of the lower sash, I secure a spring casing 12 which is formed from a substantially metallic strip bent to provide an open ended box 13 and having the ends thereof lapped and fastened by screws 14 and 15 to the sash. The box 13 receives the rod and the side walls of the box are provided with opposing vertical slots 16 and 17 which receive side lugs 18 and 19 provided on a flat spring 20 placed within the box, it being understood that the lugs are placed in the slots prior to the box being secured to the sash. The spring is bowed in a direction away from the rod and has the opposite ends thereof forming upper and lower spring catches 21 and 22 which ride the face of the rod.

The rod is provided throughout its length and at one side with a series of similar suitably spaced notches 23 which notches are in the path of travel of the spring 20 when the handle 11 is parallel to the side of the window frame or in the position as shown in Figure 2. The notches are made such that when the rod is in such latter position and the lower sash is raised, the upper spring catch 21 will slide freely into and out of the notches and the lower spring catch will slip into the notches and engage with the right angled shoulder 23'. Accordingly the lower sash can be held open in any of the desired positions by raising it until the lower spring catch 22 enters the desired notch at which time, the catch engaging the shoulder prevents the sash from dropping.

When it is desired to close the lower sash or re-adjust it in a downward direction, one swings the handle 11 to the position shown in Figure 1 and in so doing causes the notch in which the catch 22 is caught to move

away from the catch with the result that both catches are free to travel up or down the engaged surface of the rod.

It is desirable to fasten the lower sash in its closed position and I have provided a further notch 24 in the rod adjoining the lower end which notch is adapted to receive the catch 21 and by engagement therewith prevent the said sash from rising, the handle 11 at this time being parallel with the sash. When it is desired to open the lower sash, it is unlocked by swinging the handle 11, 90 degrees or from the position shown in Figure 1 to that shown in Figure 2. The 15 rotary movement of the rod so produced passes the catch 21 out of the notch 24 and so releases the sash and at the same time passes the series of notches 23 into the path of travel of the subsequently up moving 20 catches which travel with the sash as it is being opened.

It is also desirable, such as in the winter time, to have the lower sash open a small amount and fastened against movement in either direction. This is accomplished by providing a latch 25 pivotally attached to the casing 12 by the screw 15 and presenting a catch 26 adapted to enter a cross slot 27 provided in the lower part of the rod. 30 The latch 25 can be readily manipulated by the fingers and it can only be entered in the notch when the handle 11 is in the position shown in Figure 2.

The upper sash 2 is fitted also with a box 35 like spring casing 28 permanently fastened to one of the upper corners thereof by screws 29 and 30. The said casing receives the rod and it contains a spring catch 31 fastened by a rivet 32 to the said casing. The spring 40 catch 31 is adapted to ride the face of the rod and to enter the notches 23 when the rod is turned to the position shown in Figure 2 and the said sash is moved. It will be observed that the spring catch 31 extends 45 downwardly with the result that it is free to escape out of the notches in the up movement of the sash 2 and serves to hold the sash against down movement by contact with the right angled shoulder of the notch, it being 50 understood that the handle of the rod is at such time parallel with the side of the window frame. According to the above, it will be seen that the catches 22 and 31 engaging 55 the notches 23 serve to fasten the sashes in open positions.

As the turning of the handle 11, however, inwardly to a position parallel with the lower sash, would simultaneously pass both the latter catches out of the notches, it is 60 desirable to provide means for holding the upper sash closed before turning the handle. Such a device is accordingly provided and comprises a pivoted catch 33 carried centrally by the upper cross bar of the upper 65 sash and engageable with a stationary catch

34 secured to the lintel of the window frame. The catch 33 is supplied with a hand grip 35 extending normally away from the sash in the position best shown in Figure 7 and held in such position by suitable springs 36 70 provided.

When the upper sash is in the open position, the springs 36 hold the catch 33 in against the sash and when the said sash approaches the closed position, the catch 33 75 engages with the catch 34, initially moves out and then springs in and becomes caught in the position shown in Figure 7 and accordingly holds the upper sash closed. The operator can readily release the upper sash 80 by grasping the handle and pushing it towards the sash.

Usually one either opens the bottom sash or the upper sash. If the bottom sash be closed, one can release the catch 33 of the 85 upper sash and then fasten the upper sash in any desired open position by means of the catch 31 and the notches 23 and at this time, he does not require to bother about the lower sash when turning the rod as such 90 sash is closed. On the other hand, if the lower sash is to be adjusted, the upper sash is held closed by the catch 33 and it will obviously remain closed regardless of the position of the catch 31 in respect to the 95 notches 23.

Whilst I have entered into a detailed description of the structural arrangement of the catches, it will be readily understood that I do not desire to be limited to the structure shown as such could be readily structurally modified without departing from the spirit of the invention as set forth in the appended claims.

What I claim as my invention is:— 105

1. The combination with a window frame and upper and lower sashes mounted for vertical sliding movement within the frame, of a vertically disposed rod rotatably carried by the frame and having the lower end thereof provided with a handle for rotating the rod and the body of the rod provided throughout its length and at one side with a series of suitably spaced notches presenting each a right angled shoulder and a sloping face there above, spring casings 110 permanently secured to the sashes and receiving the rod and spring catches mounted in the casings and riding continuously the rod, said catches being adapted to enter 115 the notches in the raising of the sashes and fasten the sashes in various adjusted open positions and said notches being designed to release the catches in the turning of the rod under the manipulation of the handle. 120

2. The combination with a window frame and upper and lower sashes mounted for vertical sliding movement within the frame, of upper and lower brackets secured to one side of the frame, a vertically disposed rod 125

rotatably carried by the brackets and located to the inner side of the sashes and having the lower end thereof provided with a handle and the body part thereof fitted at 5 one side and throughout its length with a series of suitably spaced notches, a lower spring casing secured to one of the upper corners of the lower sash and receiving the rod, an upper spring casing secured to one 10 of the upper corners of the upper sash and receiving the rod, an upwardly extending and a downwardly extending spring catch carried by the lower casing and engaging the rod, a downwardly extending spring 15 catch carried by the upper casing and engaging the rod, said downwardly extending catches being adapted to engage the notches and hold the sashes in open positions and said upwardly extending catch being de- 20 signed to enter a single notch provided in the rod and fasten the lower sash closed, said latter notch being located in a position 90 degrees from the former notches. 3. The combination with a window frame 25 and upper and lower sashes mounted for vertical sliding movement within the frame, of upper and lower brackets secured to one side of the frame, a vertically disposed rod rotatably carried by the brackets and locat- 30 ed to the inner side of the sashes and having the lower end thereof provided with a handle and the body part thereof fitted at one side and throughout its length with a series of suitably spaced notches, a lower 35 spring casing secured to one of the upper corners of the lower sash and receiving the rod, an upper spring casing secured to one of the upper corners of the upper sash and receiving the rod, an upwardly extending and a downwardly extending spring catch 40 carried by the lower casing and engaging the rod, a downwardly extending spring catch carried by the upper casing and engaging the rod, said downwardly extending catches being adapted to engage the notches 45 and hold the sashes in open positions and said upwardly extending catch being de- 50 signed to enter a single notch provided in the rod and fasten the lower sash closed, said latter notch being located in a position 90 degrees from the former notches and releasable means for locking the upper sash to the upper part of the frame. 4. The combination with a window frame and a lower sash mounted for vertical sliding movement within the frame, of a vertically disposed rod rotatably carried by the frame to the inner side of the sash, said rod being provided throughout its length and at one side with a series of suitably spaced 55 notches, a spring catch carried by the sash and riding the rod and engageable with the notches thereof in the opening of the sash and a latch pivotally mounted on the sash and engageable with a cross slot in the 60 lower end of the rod.

Signed at Winnipeg, this 29th day of September, 1926.

ALEXANDER G. CAMERON.
